UNITED STATES PATENT OFFICE.

ADOLPH J. ZIMMERMANN, OF NEW ORLEANS, LOUISIANA.

COMBINED HAMMER AND SCREW-DRIVER.

No. 875,880.

Specification of Letters Patent.

Patented Jan. 7, 1908.

Application filed May 28, 1907. Serial No. 376,082.

To all whom it may concern:

Be it known that ADOLPH J. ZIMMERMANN, a citizen of the United States, residing at 416 Carondelet street, New Orleans, in the 5 parish of Orleans and State of Louisiana, has invented certain new and useful Improvements in a Combined Hammer and Screw-Driver, of which the following is a specification.

10 This invention relates to tools and more particularly to combination tools and has for its object to provide a tool of this variety which will include a hammer including the usual head and handle and a screw driver or 15 other bit arranged for movement into and out of the handle, the invention also including means for holding the bit at times in retracted and at times in projected position.

Another object is to provide a tool of this 20 kind so arranged that the head will act as a transverse handle by which the bit may be turned.

Other objects and advantages will be apparent from the following description and it 25 will be understood that changes in the specific structure shown and described may be made within the scope of the claims, without departing from the spirit of the invention.

In the drawings forming a portion of this 30 specification, and in which like numerals of reference indicate similar parts in the several views, Figure 1 is an elevational view of the present tool with the bit extended; Fig. 2 is a longitudinal section through the handle 35 with the bit in the position shown in Fig. 1; Fig. 3 is a sectional view through the handle with the bit removed, to illustrate the retaining slots; Fig. 4 is a longitudinal section with the bit retracted. Fig. 5 is a trans- 40 verse sectional view of the handle.

Referring now to the drawings, the present invention comprises a handle 5 carrying a transverse hammer head 6 at one end. The handle has a longitudinal passage 7 formed 45 therewithin and opening through its lower end, and in this passage there is a bit 8 which is slidable to lie at times within the passage and to project at times beyond the end of the handle.

50 Formed in the wall of the passage 7, there is a longitudinal groove 9 which, at its upper end, has a lateral extension 10 provided with a pocket 11 at its distal end from the groove 9. Adjacent to its lower end, the groove 9

has an extension which is turned laterally as 55 shown at 12 and then upwardly as shown at 13, and these grooves receive a lateral projection 14 which is carried by the bit 8, for sliding movement of this projection in the grooves. 60

When the projection 14 is at the upper end of the groove 9, the end of the bit projects slightly beyond the lower end of the handle and thus the bit may be grasped and turned to bring the projection into the extension 10 and thence into the pocket 11 when the bit will be held within the handle as will be readily understood.

When the bit is at the outward limit of its movement, the projection 14 may be moved 70 into the extension 12 through rotation of the bit, and when the tool is in use, the projection may be brought into the portion 13 of the extension to prevent return of the projection into the groove 9 when the handle is 75 rotated. Means is thus provided for holding the bit at times retracted and at times projected.

What is claimed is:

In a combination tool, the combination 80 with a handle having a transverse tool head at its upper end, the handle having a longitudinal passage therewithin opening through the opposite end of the handle from the tool head, the end of the passage adjacent to the 85 tool head being closed, said handle having a longitudinally extending interior groove formed in the wall of the passage, said groove having a laterally and downwardly turned angular extension at its upper end and having a laterally and upwardly turned extension at its lower end, said extensions lying at a common side of the groove, of a bit slidably mounted in the passage and having a lateral projection extended into the groove for 90 movement therein and arranged to lie at times in the downwardly turned portion of the upper lateral extension to hold the bit retracted within the handle, and at times within the upwardly turned portion of the 100 lower lateral extension, to hold the bit projected from the handle.

In testimony whereof I affix my signature, in presence of two witnesses.

ADOLPH J. ZIMMERMANN.
